(57) **CLAIM**

The ornamental design for a throwable rescue reel, as shown and described.

DESCRIPTION

FIG. 1 is a front elevational view of a throwable rescue reel showing my new design, the rear, left side and right side views being the same thereas;

FIG. 2 is a top plan view thereof, the bottom plan view being the same thereas; and,

FIG. 3 is a perspective view thereof.

The broken lines shown in FIG. 3 are for illustrative purposes only and do not form part of the claimed design.
